UNITED STATES PATENT OFFICE.

ALFRED W. TANNER, OF ROCK ISLAND, ILLINOIS.

MOLDING-MACHINE.

1,123,035.

Specification of Letters Patent. Patented Dec. 29, 1914.

Application filed April 2, 1910. Serial No. 553,024.

To all whom it may concern:

Be it known that I, ALFRED W. TANNER, a citizen of the United States, residing at Rock Island, in the county of Rock Island and State of Illinois, have invented certain new and useful Improvements in Molding-Machines; and I do hereby declare the following to be a full, clear, and exact description of the invention, such as will enable others skilled in the art to which it appertains to make and use the same.

This invention relates to improvements in molding machines, and particularly to compressed air machines for closely packing and molding sand around the pattern or mold in a flask.

The object in view is the provision of a plurality of associated means for packing sand around a pattern or mold by the use of compressed air which forces the sand properly in place and causes a proper distribution of the same.

A further object of the invention is the arrangement in a machine of the class described of a hopper provided with a pivotally mounted nozzle and a feeding screw located in the hopper for forcing sand into the nozzle, in combination with air feeding means for mixing with the sand during the discharge thereof so as to cause the sand to pack in the flask properly around the pattern.

With these and further objects in view, the invention comprises certain novel constructions, combinations and arrangements of parts as will be hereinafter more fully described and claimed.

In the accompanying drawings,—Figure 1 is a side elevation of an embodiment of the invention. Fig. 2 is a vertical sectional view through a hopper, nozzle and surrounding parts embodying certain features of the invention.

In forming a molding machine embodying the invention the same is provided with a hopper, containing sand to which hopper is connected a pivotally mounted nozzle having any desired kind of opening therein. This nozzle is mounted so as to move in any direction so as to cause the discharge of sand from the hopper to any point in a flask placed near the nozzle. In the hopper is arranged a feeding screw for positively forcing or feeding sand into the nozzle. In addition to the screw for feeding the sand into the nozzle a tube is passed through the

shaft of the sand feeding screw and into a short distance of the nozzle for providing an air blast for the sand in order that the sand may be properly packed around the pattern 60 in the flask. A compressed air tank is provided for maintaining any desired air pressure for the air pipe leading to the discharge nozzle and also for providing pressure for a hand nozzle which is used as an auxiliary 65 means for blowing off any loose sand or foreign substance that may be in, or on the mold, at any point desired.

In order that the invention may be more clearly understood, an embodiment of the 70 same is shown in the accompanying drawings in which—

1 indicates a hopper for containing sand. This hopper may be of any desired size, but is preferably formed conical and merges 75 into a discharge pipe 2 having a particlularly globular enlargement 3 over which fits a similar enlargement 4 of nozzle 5. This arrangement of nozzle and enlargements provides a universal joint arrangement for 80 the nozzle in order that the same may be moved as desired for directing and packing sand in flask 6.

Mounted in hopper 1 is a feeding screw 7 which tapers approximately proportionately to the taper of hopper 1 and is designed to stir the sand in hopper 1 and to force the same in a steady stream into pipe 2 and from thence out nozzle 5. In order that screw 7 may be moved or rotated, the shaft 8 thereof has secured thereto a gear 9 which meshes with gear 10. Gear 10 is carried by shaft 11 which receives power through a belt 12 and pulley 13. When screw 7 is not working belt 12 is shifted to the idler 14 90 so that the various parts will not be under any strain or tension. In order to shift belt 12 treadles 15 and 16 are provided which are connected to belt shifter 17 by means of cables or ropes 18 and 19. These cables or ropes pass over suitable pulleys 20 and 21 and are connected to belt shifter 17 in any desired manner for causing the same to slide in its supports 22 and 23. By this arrangement whenever it is desired to feed sand 100 from hopper 1 treadle 16 is depressed for moving belt 12 to pulley 13. When this is done power is transmitted through the mechanism above set forth to screw 7 for causing the same to force the sand into nozzle 5 and from thence into flask 6. At the same time that screw 7 is placed in opera-

- tion, the hand operated valve 24 is turned on for permitting compressed air to escape from tank 25 to pipe 26 through pipes 27 and 28. Pipe 26 extends through the shaft 5 of screw 7 and downwardly to near the lower end of pipe 2 for mixing the sand just previously to the discharge of the same for causing the sand to be sprayed and packed tightly about the pattern or mold in the 10 flask. If for any reason there should be any loose sand or foreign substance in, or on the mold, air may be turned on at 29 for supplying compressed air to pipe 30, which air will be discharged out of nozzle 31 and 15 thereby remove said loose sand or foreign substance. Pipe 30 is a flexible pipe and may be of any desired length, so that nozzle 31 may be manually moved about flask 6 for blowing off loose sand or foreign substances.
- 20 Tank 25 is maintained supplied with compressed air by a suitable pump 32, but obviously if there is an air line available, pressure therefrom can be utilized in lieu of the tank and pump.
- 25 What I claim is:—
1. In a device of the class described, a sand containing hopper, a nozzle having a universal joint connection with the lower portion of the hopper, a positive mechani- 30 cal feed for forcing the sand from the hopper into the nozzle, means for discharging compressed air longitudinally centrally through the nozzle during the delivery of sand therethrough, the hopper and nozzle being disposed for the feeding of the sand 35 through the nozzle by gravity, and means supplemental to the air supply pipe for delivering a blast of air to the sand discharged from the nozzle for removing loose sand.
  2. In a device of the class described, a sand containing hopper, a nozzle having a ball and socket joint connection with the lower portion of the hopper, a screw within the hopper, means for rotating the screw for 40 mechanically forcing sand downwardly in the hopper toward the nozzle thereof, the screw being axially tubular, and means for delivering air under pressure through the screw and delivering the sand into the nozzle 45 axially thereof at a point below the lower end of the screw.

In testimony whereof I affix my signature in presence of two witnesses.

ALFRED W. TANNER.
